RESILIENT SUPPORT

Filed Sept. 4, 1928

John J. White Inventor

By *Herbert E. Smith*

Attorney

UNITED STATES PATENT OFFICE

JOHN J. WHITE, OF SPOKANE, WASHINGTON

RESILIENT SUPPORT

Application filed September 4, 1928. Serial No. 303,811.

My present invention relates to an improved resilient support or carrier for use upon vehicles, and while the support is capable of use with various objects or articles to be transported it is especially designed for the purpose of supporting portable outboard motors for boats. As is well known these motors are attached to and removable from the stern of the boat as desired, and frequently the boat owner is called upon to transport the motor from the boat to a storeroom. The parts of the motor are susceptible to breakage or damage in rough handling when the motor is out of its proper element, and to overcome these dangers in carrying the motor from the storeroom to the boat or vice versa, I have invented a resilient support which is attachable to the running-board of an automobile. The resilient support is provided with means whereby a motor may be carried without danger of breakage, and the support is designed to act as a shock absorber to prevent transmission of vibrations from the traveling automobile to the motor. Means are provided whereby the support may with facility be attached to or detached from the automobile, and means are provided whereby the outboard motor may be properly held in position on the support so that it may be transported without danger of accidental displacement.

The invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have so far devised for the practical application of the principles of my invention.

Figure 1 is a perspective view showing so much as is necessary of an automobile for the purpose of illustrating the attachment thereto of the support of my invention, the outboard motor being shown carried by the support. Figure 2 is a view in side elevation of the support. Figure 3 is a top plan view of the support. Figure 4 is a front end view of the support.

In order that the general assembly and re-

lation of parts may readily be understood I have indicated in Figure 1 a portion of an automobile as A having a usual running-board R. The outboard motor that is illustrated in Figure 1 is of conventional type for use with boats and comprises the motor M and the propeller P, and also includes an attaching yoke Y by means of which the motor is attached at the stern of the boat.

In carrying out my invention I use a baseboard as 1 which is approximately the width of the running-board R and somewhat shorter in length than the running board. A springboard 2 is hinged at 3 at one end of the baseboard and near the forward ends of the baseboard and springboard a pair of vertical guide plates 4 are used. The guide plates are attached to the opposite edges of the baseboard and they are of sufficient length to act as guides for the free end of the springboard 2.

The baseboard is provided with a guide bolt 5 which projects through an opening in the springboard and above the springboard a spring 6 is coiled about the bolt and interposed between the head of the bolt and the upper face of the springboard. Between the baseboard and the springboard a pair of springs 7, 7 are interposed and it will be apparent that these three springs provide a resilient support for the springboard above the baseboard so that the springboard may move relatively to the baseboard and any shocks or vibrations transmitted to the springboard from the runningboard and baseboard will be absorbed by these springs.

On the upper face of the springboard a bench 8 is provided and secured in an inclined plane by means of blocks 9 and 10 to the springboard. The support may be attached to the runningboard in suitable manner, as for instance by the use of clamps 11 and clamp bolts 12 located near the forward and rear ends of the support. These clamp devices rigidly secure the support to the runningboard but they also insure facility in removing the support from the runningboard when the support is not needed.

The outboard motor is attached to the support through the instrumentality of its yoke

Y and clamps 13, in the same manner that the outboard motor is attached to the boat which is to be propelled.

As thus illustrated and described it will be apparent that the outboard motor may be transported on the automobile without danger of accidental displacement and also without danger of breakage or damage due to excessive shocks or vibrations of the traveling automobile.

Having thus fully described my invention, what I claim as new and desire to secure by Letters Patent is:

1. The combination in a resilient support with a baseboard and a hinged springboard and guide means for the springboard, of resilient means at opposite sides of the springboard for absorbing movement of the springboard relatively to the baseboard.
2. The combination in a spring support adapted for use with a vehicle of a baseboard and a springboard hinged thereto, side guide plates for the springboard, a pair of springs between the springboard and the baseboard, and a spring located against the outer face of the springboard.
3. The combination with a baseboard, a hinged springboard, and side guide plates, of a pair of springs between the springboard and the baseboard, a bolt in the baseboard passing through the springboard and a spring on said bolt bearing against the outer face of the springboard and an inclined bench secured to the outer face of the springboard.

35 In testimony whereof I affix my signature.

JOHN J. WHITE.
